UNITED STATES PATENT OFFICE.

HENRIK WIKING, OF GOTTERBORG, SWEDEN.

OIL CAN.

Application filed July 6, 1925. Serial No. 41,774.

The present invention relates to oil-cans of the kind comprising a receptacle for the oil and a force and suction pump for forcing the oil out through a discharge pipe.

5 The primary object of this invention is to provide an oil-can of this type which will not leak if the can be placed in lying or inclining position (which might easily occur when the oil-can is stored for instance in 10 the tool box of an autocar).

Another important object of the invention is to provide the discharge pipe in such a manner that said pipe can be swung or adjusted to any desired position in relation to 15 the receptacle whereby places which otherwise are accessible only with difficulty readily can be reached by the oil-can.

These and other objects of the invention will be understood by the following description 20 with reference to the accompanying drawing illustrating one preferred embodiment of the invention.

Referring to the drawing, Figure 1 shows 25 a vertical section of the oil-can, Figure 2 a side elevation of a portion of the oil-can, Fig. 3 a similar view with the discharge pipe removed and Figures 4-6 views of details showing the device by means of which the discharge pipe is joined to the receptacle.

30 In the drawing, 1 denotes the receptacle fitted with a pump-cylinder 2 preferably arranged in inclining position in said receptacle which is provided with a discharge pipe 3 and a handle 4. The piston of the force and suction pump is denoted by 5 and the piston rod, having a button 6 on its outer end, by 13. The pump-piston 5 is actuated by a spring 11 by which the piston, when at rest, is kept raised and forced 35 against the end of a tube 110 fastened to the cover 12 of the pump-cylinder and through which the piston rod passes. The air is permitted to enter into the pump-cylinder through said tube in the downward movement of the piston and to escape 40 through it in the upward stroke thereof. The inlet for the oil is denoted by 7 and is closed in an oil-tight manner by a screw-cap 8.

45 In order to permit the air to enter into the receptacle in the operation of the pump, said entering of air being necessary for forcing out the oil, a small bore or opening is arranged in the top 35 of the receptacle, the said bore or opening receiving the end of 50 one branch 14^a of a rather thin U-shaped pip-

ing 14 preferably extending adjacent to the bottom of the receptacle. The other branch 14^b of said piping extends upwards and adjacent the under side of the top 35 of the 60 receptacle.

The pump-cylinder 2 communicates with a suction-canal 15 controlled by a ball 16, which is forced against its seat by a spring 17, as well as with a delivery-canal 18 which 65 is controlled by a ball 19 acted upon by a spring 20. From the delivery-canal 18 a pipe-connection 21 passes to the discharge pipe 3 which is united to said pipe-connection by means of a joint permitting the adjustment of said discharge pipe in any desired position. Said joint comprises a member 22 fastened to the bottom of the receptacle. A central boring 23 in this member 70 by means of a hole 24 going through the top wall of the member and the bottom of the receptacle communicates with the pipe-connection 21. A rotatable pin 25 of essentially smaller diameter than that of the boring 23 is inserted into the latter leaving a passage 75 for the oil in the interspace between the member 22 and the pin. One end of said pin is provided with threads receiving a nut 27 by means of which a head 29 upon the other end of the pin is forced against an offset 30 80 at one end of the member 22, a packing ring 31 being preferably provided between the head 29 and the offset 30. The nut 27 bears against an inwardly extending flange 32 at the opposite end of the member 22, a washer 85 33 and a packing ring 34 being preferably provided between the nut and the flange. When tightening the nut 27 to a certain degree a shoulder 35 on the pin 25 will bear against the inner side of the flange 32. By 90 the device described both ends of the member 22 will be closed in an oil-tight manner at the same time as rotation of the pin 95 is permitted.

The boring 23 of the member 22 communicates with a central boring 36 in the pin 25 which boring extends from the interspace between the pin 25 and the member 22 to the interior of the head 29 and communicates 100 there with a boring 37 the axis of which is perpendicular to the axis of the boring 36. A member 38 having a central boring 38^a disposed co-axially to the boring 37 and communicating with the latter is revolvably attached to the head 29. The member 38 is 105 joined to the head 29 by a screw 39 of smaller diameter than that of the borings 37 110

and 38^a. The head 39^a of said screw by means of a packing ring 40 bears against an inwardly extending flange 41 on the head 29. The threaded end of the screw or pin 39 receives a nut 42 bearing against the outer side of the member 38. An oil-tight connection between the parts 29, 38 is effected in the following manner: On the head 29 there is provided a flange 43 projecting co-axially in relation to the boring 37 and surrounded by an annular recess 44 (Figure 5). This recess, in which a packing ring 45 is applied, fits to a flange 46 projecting from the member 38 and co-axially positioned in relation to the boring 38^a. When the nut 42 is tightened the flange 46 will bear tightly against the packing ring 45. The member 38 (Figure 6) is formed with a threaded portion 47 having a boring 48 therein. The threaded portion 47 receives a nut 49 by means of which a flange 50 on the end of the discharge pipe 3 is forced against the outer end of the portion 47. A packing ring 51 may be provided between the flange 50 and the nut 49. By these means the discharge pipe 3 is permitted to be rotated about its longitudinal axis as well as about each of the pivots 25 and 39. The pivot 39 permits the swinging of the discharge pipe in a vertical plane and the pivot 25 in any plane forming a right angle to said vertical plane. Due to this arrangement the discharge pipe can be adjusted to any desired inclining position which involves a great advantage in the lubrication of difficultly accessible places.

On the outer end of the discharge pipe 3 a screw-cap 52 or the like may be applied in order to prevent leakage of oil through said pipe.

Two studs 53 attached to the bottom of the receptacle 1 together with the member 22 form supports for the oil-can.

Supposing oil is present in the receptacle to the height indicated in Figure 1. If now the pump-piston 5 be moved downwards against the action of the spring 11 the oil previously sucked into the pump-cylinder will be forced out through the discharge pipe 3. When the piston 5 is pressed upwards by the spring 11 a new quantity of oil is sucked through the canal 15 into the pump-cylinder on the under side of the piston. Hereby a reduction of the pressure in the space 35^a above the oil within the receptacle will take place and as a consequence air will be supplied into said space through the U-shaped piping 14. The air thus supplied obviously replaces the oil sucked into the pump-cylinder. Under ordinary conditions no oil will be able to escape through the piping 14 even if the can be placed in lying or inclining position, but if any small quantity of oil has entered into the piping it will be pressed out into the receptacle at the next upward stroke of the piston 5 by the air

which at the same time by the atmospheric pressure is forced into the piping.

It will thus be understood that the oil-can is completely oil-tight at all parts where otherwise a leakage might easily take place. If on account of heat the volume of the oil be increased the air is permitted to escape from the space 35^a through the pipe 14. If such an escaping of the air were not possible the pressure within the receptacle would be increased and the oil forced out through the discharge pipe.

I do not limit my invention to the embodiment above described with reference to the drawing but want to be free to vary the details thereof without departing from the spirit of the invention as defined in the appended claims.

What I claim is:

1. In oil-cans, a receptacle for the oil, a force and suction pump comprising a pump-cylinder and a piston movable within it, a discharge pipe adapted to communicate at times with the delivery-canal of the pump, a joint comprising two members having borings forming a passage for the oil between the delivery-canal and the discharge pipe, a pin passing through said borings and rotatably connecting said members with each other, a flange on one of said members engaging with a recess on the other member, and one of said members connected to the discharge pipe by a joint adapted to permit the rotation of said pipe about its own axis.

2. In oil-cans, a receptacle for the oil, a force and suction pump comprising a pump-cylinder and a piston movable within it, a discharge pipe adapted to communicate at times with the delivery canal of the pump, a joint comprising two members having borings forming a passage for the oil between the delivery-canal and the discharge pipe, a pin passing through said borings and rotatably connecting said members to each other, one of said members having a threaded portion extending about perpendicularly to the axis of the borings of the members and provided with a boring communicating with the first mentioned borings, said threaded portion carrying a nut engaging with a flange on the discharge pipe so as to force said flange against the extreme end of the threaded portion, whereby the discharge pipe is retained in position but its rotation about the axis of the pipe permitted.

3. In oil-cans, a receptacle for the oil, a force and suction pump comprising a pump-cylinder and a piston movable within it, a discharge pipe adapted to communicate at times with the delivery canal of the pump, a joint comprising two members having borings forming a passage for the oil between the delivery canal and the discharge pipe, a pin passing through said borings and

rotatably connecting said members to each other, one of said members constituting a part of a pivot pin forming a passage for the oil from the pump, the said pins disposed substantially at right angles to each other and adapted to enable the swinging of the discharge pipe in separate planes.

4. The combination with an oil can and a discharge spout therefor, of a joint connection between said oil can and spout comprising a stationary member having a bore therein communicating with the oil can a swinging member having a bore therin

communicating with the spout, a pin rotatably connected to said stationary member and having a longitudinally extending bore communicating with the bore of said stationary member, an enlarged head formed on one end of said pin and means for rotatably connecting said enlarged head of said pin to said swinging member as and for the purpose specified.

In witness whereof I have hereunto set my hand.

HENRIK WIKING.
